Primary Examiner — Jonathan J Han*Assistant Examiner* — Amanda J Berlinski(74) *Attorney, Agent, or Firm* — Connie R. Masters(57) **CLAIM**

The ornamental design for a tattoo device, as shown and described.

DESCRIPTION

FIG. 1 is a front perspective view of a tattoo device, showing my new design;

FIG. 2 is a rear perspective view thereof;

FIG. 3 is a top view thereof, where the left side view, right side view, and bottom view are identical to the top view;

FIG. 4 is a front view thereof;

FIG. 5 is a rear view thereof; and,

FIG. 6 is an exploded right side view thereof showing the tattoo device with an attachment.

The broken lines in FIG. 2, FIG. 4, and FIG. 5 depict portions of the tattoo device that form no part of the claimed design. The broken lines in FIG. 6 depict environmental subject matter that forms no part of the claimed design.
